UNITED STATES PATENT OFFICE.

GUSTAV A. KRUTTSCHNITT, OF NEWARK, NEW JERSEY.

DESIGN FOR A BOX.

No. 39,238.

Specification for Design.

Patented March 31, 1908.

Application filed January 20, 1908. Serial No. 411,824. Term of patent 7 years.

To all whom it may concern:

Be it known that I, GUSTAV A. KRUTTSCHNITT, a citizen of the United States, residing in Newark, county of Essex, and State of New Jersey, have invented a new, original, and ornamental Design for a Box, of which the following is a specification, reference being had to the accompanying drawing, forming part thereof.

The figure is a front elevation of the box, showing my new design.

I claim:

The ornamental design for a box, as shown.

GUSTAV A. KRUTTSCHNITT.
